(57) **CLAIM**

The ornamental design of a deck boat, as shown and described.

DESCRIPTION

FIG. 1 is a perspective view from the rear and left side of a deck boat showing our new design;

FIG. 2 is the same perspective illustration, showing an alternative arrangement of two of the seat cushions at a rear portion of the deck boat of our design;

FIG. 3 is another perspective view from the front and left sides of FIG. 1;

FIG. 4 is a front view thereof;

FIG. 5 is a rear view thereof;

FIG. 6 is a top view thereof;

FIG. 7 is a bottom view thereof;

FIG. 8 is a left side view thereof; and,

FIG. 9 is a right side view thereof.

Where included, broken lines showing environment or structure are for illustrative purposes only and form no part of the claimed design.

The omission of a view indicates that the omitted view is plain and unornamented.
